(74) Attorney, Agent, or Firm — Cislo & Thomas, LLP

(57) CLAIM

The ornamental design for a blanket with sleeves, inside foot pockets and open back, as shown and described herein.

DESCRIPTION

FIG. 1 is a front elevation view of the blanket with sleeves, inside foot pockets and open back, showing my new design; FIG. 2 is a rear elevation view thereof; FIG. 3 is a left side elevation view thereof; FIG. 4 is a right side elevation view thereof; FIG. 5 is a top plan view thereof; and, FIG. 6 is a bottom plan view thereof.
The broken lines are for environmental purposes only and form no part of the claimed design.

1 Claim, 4 Drawing Sheets
